UNITED STATES PATENT OFFICE

154,897

DESIGN FOR A BASQUE SHIRT

Bud Berman, New York, N. Y., assignor to Bud Berman Sportswear, Inc., New York, N. Y., a corporation of New York

Application December 17, 1948, Serial No. 150,213

Term of patent 3½ years

(Cl. D3—4)

To all whom it may concern:

Be it known that I, Bud Berman, a citizen of the United States, resident of the city of New York, in the county of Queens, State of New York, have invented a new, original, and ornamental Design for a Basque Shirt, of which the following is a specification, reference being had to the accompanying drawing, forming part thereof.

In the drawing,

I claim:

The ornamental design for a basque shirt, substantially as shown.

BUD BERMAN.
